UNITED STATES PATENT OFFICE.

JOSEPH C. DERROUGH, OF HOBART, OKLAHOMA, ASSIGNOR OF ONE-HALF TO STEPHEN A. HOLCOMB, OF HOBART, OKLAHOMA.

GARBAGE-CREMATORIAL.

1,177,498.

Specification of Letters Patent.

Patented Mar. 28, 1916.

Application filed March 30, 1915. Serial No. 18,172.

To all whom it may concern:

Be it known that I, JOSEPH C. DERROUGH, a citizen of the United States, residing at Hobart, in the county of Kiowa and State of Oklahoma, have invented new and useful Improvements in Garbage-Crematories, of which the following is a specification.

The invention relates to refuse burning furnaces, and has for an object to provide 10 a crematory for effectually burning garbage and similar waste matter.

The invention contemplates, among other features, the provision of a crematory so constructed and arranged that garbage 15 placed therein will be entirely incinerated and will, particularly when the garbage is wet or moist, be gradually dried, charred and then consumed by the intense heat produced in the body of the furnace.

20 Still further embodiments of the invention reside in a garbage crematory in which provision is made to effectually consume the gases which are formed and pass off during the process of incineration of the garbage, 25 these gases being received in a compartment adjacent the usual stack or outlet flue and in which compartment the gases, subjected to an intense heat, will result in the combustion of the matter contained in the gases 30 so as to reduce obnoxious odors which ordinarily would pass out through the stack.

In the further disclosure of the invention reference is to be had to the accompanying drawings, constituting a part of 35 this specification, in which similar characters of reference denote corresponding parts in all the views, and in which:

Figure 1 is a vertical longitudinal sectional view taken through the furnace on 40 the line 1—1 in Fig. 2; Fig. 2 is a horizontal sectional view of the furnace, taken on the line 2—2 in Fig. 1; Fig. 3 is a vertical transverse sectional view taken on the line 3—3 in Fig. 1; Fig. 4 is a vertical sectional view taken on the line 4—4 in Fig. 1; and Fig. 5 is a vertical sectional view taken on the line 5—5 in Fig. 2, looking in the direction of the arrow.

Referring more particularly to the views, 50 10 represents the base, the front wall being indicated by the numeral 11 and the rear wall by the numeral 12, said front and rear walls 11 and 12 and the bottom or base 10, together with side walls 13 and 14 and an 55 arched roof 15, forming a casing 16 into

which the garbage is to be dumped through a substantially circular hopper 17 formed in the roof of the casing. The walls forming the casing are built of brick and the casing is suitably lined with a firebrick or other refractory material, suitable buckstays or other reinforcing rods 18 being provided to pass through the side and end walls and also through the roof in order to substantially reinforce the entire structure. 60 It will be noted that although the exterior of the casing is of substantially a rectangular construction, the inner wall of the casing is not defined by the usual corners but at its rear is curved as shown. The front 65 wall 11 is preferably covered with a cast iron or other suitable shell 19 which, if desired, may also cover the entire structure. A flue 20 is formed in the side wall 14 to connect with a passage 21 sufficiently large 70 to be termed a compartment, said compartment being formed by a continuation of the front wall 11 and walls 22. The compartment 21 terminates in a stack 22' upstanding at one end of the compartment. A suitable 75 opening 23 in the front wall 11 communicates with a firebox 24 formed in the casing 16, said firebox being provided with a grate 25 and a hopper 26 arranged to supply fuel to the grate 25. An upstanding wall substantially triangular in cross section and indicated by the numeral 27 forms the firebox with the side wall 13, with the face of the wall forming the firebox extending substantially at right angles to the front of the furnace, the other face of the upstanding wall 27 being inclined as shown, with a grate-like platform 28 arranged in this portion of the casing and adjacent to the inclined face of the upstanding wall 27 and 80 which therefore substantially separates the grate 25 from the grate-like platform 28, said grate-like platform 28 being adapted to have the residue of the consumed garbage raked thereon to fall through the grate-like 85 platform beneath which an opening 29 is provided so that the consumed matter or ashes can be removed from the casing.

The compartment 21 has a right angled extension forming a firebox 30 communicating with the exterior by an opening 31 for the removal of ashes and the like, a grate 32 being arranged in the firebox 30, with a hopper 33 communicating with the firebox to supply fuel to the grate. A wall in the 90 105 110

nature of a bridge-wall 34 is arranged to extend transversely to the portion of the compartment 21 extending at right angles thereto and which forms the firebox as mentioned, 5 and it will be clearly seen that the firebox 30, together with its grate 32 and hopper 33, affords a conveniently arranged means for a fire producing an intense heat which will result in the production of an intense 10 temperature in the compartment 21. A second flue 31' is formed in the side wall 14 for the purpose of establishing direct communication of the fire chamber 30 with the grate 28.

15 The casing 16 is in the nature of a storage chamber and a suitable closure 35 having been removed to uncover the hopper 17 the garbage that is to be incinerated is dumped into the hopper and will be received in the 20 storage chamber. A fire having been produced upon the grate 25 with the fuel fed to the fire through the hopper 26, an intense heat will result in the casing or storage chamber, thus charring the garbage and gradually evaporating the moisture therefrom until the garbage reaches a point where it will be substantially consumed, the heat in the storage chamber impregnating the garbage and reaching every particle thereof 25 to effect as near a perfect combustion of the garbage as can be obtained. As the garbage is consumed it is raked on to the platform 28 and which, as mentioned, is somewhat in the nature of a large grate with the consumed 30 or ash part of the garbage adapted to filter through the grate and be removed through the ash removal opening 29 mentioned heretofore. Now the gases, which necessarily will be produced when the garbage is 35 consumed, passing from the storage chamber, will pass through the flue 20 into the compartment 21 and in view of the fact that this compartment is subjected to an intense heat from the fire upon the grate 32, it will 40 be clearly apparent that the foreign particles will pass into the compartment 21 and the obnoxious gases will be almost entirely consumed by the intense heat of the compartment so that the residue which passes up 45 through the stack 22' will be substantially devoid of obnoxious odors. Thus it will be seen that the stack 22' providing a sufficient draft for the heat produced in the storage chamber to circulate around and penetrate 50 the garbage will result in the consumption and incineration of the garbage in the manner mentioned, the curvature of the walls of the storage chamber and the arching of the roof, however, being important factors in 55 guiding the heat currents so that they will effectively impregnate the garbage in the storage chamber and result in its effective incineration in the manner mentioned.

With the construction set forth it will be 60 clearly apparent that the stack 22' will be

substantially smokeless in view of the consumption of the gases as they pass from the storage chamber into the gas consuming compartment 21 and by having the gases pass out of the storage chamber and into the compartment 21 they will not hinder the proper incineration of the garbage in the compartment and will aid in rendering the incineration more effective in that they will not clog the chamber to prevent the proper 75 draft and the proper circulation of the heat currents produced in the firebox 24 and upon the grate 25 thereof. Therefore, in the construction of the apparatus shown it will be clear that the incinerating furnace described 80 will have its casing or storage chamber and also its gas consuming compartment heated to a maximum temperature to incinerate the garbage and evaporate any moisture contained therein and also consume the gases 85 which are produced during the incinerating operation, this latter mentioned waste matter being effectually consumed to the extent that the stack provided as an outlet for the entire structure will be substantially smoke- 90 less and devoid of gases and odors that would ordinarily escape through the stack if they were not subjected to an intense heat for the purpose of consuming the same.

95 The side wall 13 is formed with a bulged portion 36 providing an auxiliary chamber 37 forming a firebox which has communication with the casing 16 by means of a passage 38, said auxiliary firebox having a grate 39 therein, with a suitable opening 40 closed 100 by a door 41 permitting the removal of ashes beneath the grate, an auxiliary hopper 42 being provided in the roof or top for feeding dry garbage under the grate as fuel.

105 The auxiliary firebox described is provided as an additional means for drying out the wet garbage from the main storage chamber or casing and the fireboxes for drying out the garbage can be simultaneously or alternately operated so that if it is desired one can be cleaned out while the other is in use or both can be operated at the same time. It will be further noted by reference 110 particularly to Fig. 2 that the provision of the auxiliary chamber and its fireboxes presents a structure in which the necessary heat required to incinerate the garbage can be governed with respect to the amount of garbage to be incinerated at one time in the furnace, and to this end, if the incinerator 120 is not working at its full capacity and is not filled with garbage to its fullest extent, the operator can, if he desires, use only one of the fireboxes and place it in operation to produce the desired number of heat units 125 necessary to incinerate the garbage contained in the storage chamber. On the other hand, if the storage chamber is loaded to its full capacity the main firebox and auxiliary firebox can be set in operation and the fires 130

produced therein will generate sufficient heat to incinerate the full amount of garbage contained in the storage chamber.

Having thus described my invention, I claim:

A garbage crematory embodying a storage chamber, a fire box in said chamber, a fuel grate for the fire box, an ash grate in said storage chamber, a wall interposed between 10 said grates, a compartment communicating with the storage chamber by means of a flue on one side thereof, a fire box in said compartment and having direct communica-

tion with the grate of the storage chamber by means of a second flue, an auxiliary 15 chamber, a grate in said last mentioned chamber, the latter mentioned chamber communicating with the storage chamber by means of a passage.

In testimony whereof I affix my signature 20 in presence of two witnesses.

JOSEPH C. DERROUGH.
